UNITED STATES PATENT OFFICE.

NAPOLEON DU BRUL, OF CINCINNATI, OHIO.

DESIGN FOR A HOPPER-FRAME.

SPECIFICATION forming part of Design No. 24,931, dated November 26, 1895.

Application filed October 22, 1895. Serial No. 566,561. Term of patent 14 years.

To all whom it may concern:

Be it known that I, NAPOLEON DU BRUL, citizen of the United States, and a resident of Cincinnati, in the county of Hamilton and State of Ohio, have invented and produced a new and original Design for a Hopper-Frame, of which the following is a specification, reference being had to the accompanying drawings.

Figure I is a front elevation of the hopper-frame, showing my design. Fig. II is a side elevation. Fig. III is a rear elevation. Fig. IV is a top view.

The leading features of my design consist in the upwardly-flaring front portion, the upwardly-flaring rear portion, and the standard located between the front portion and the rear portion.

1 is a standard, having an opening 2 surrounded by a ring or annular projection 3. 20 Projecting forward from the lower side of the opening is an upwardly-flaring front portion 4, and extending over the ring or annular projection is an upwardly-flaring rear portion 5. 25

Having thus described my invention, the following is what I claim as new therein and desire to secure by Design Letters Patent:

The design for a hopper-frame substantially as herein shown and described.

NAPOLEON DU BRUL.
